Primary Examiner — Rachel A. Voorhies*Assistant Examiner* — Benjamin D. Wannemacher(74) *Attorney, Agent, or Firm* — LegalForce RAPC Worldwide(57) **CLAIM**

The ornamental design for a tri-groove socket, as shown and described.

DESCRIPTION

FIG. 1 is a front top-left side perspective view for a tri-groove socket, showing our new design;

FIG. 2 is a rear bottom-right side perspective view of FIG. 1 thereof;

FIG. 3 is a front top-left side perspective view of FIG. 1 thereof;

FIG. 4 is a front elevational view of FIG. 1 thereof;

FIG. 5 is a rear elevational view of FIG. 1 thereof; and,

FIG. 6 is a left side elevational view of FIG. 1 thereof, the right side elevational view, top plan view and bottom plan view being a mirror image.

1 Claim, 6 Drawing Sheets(56)
